UNITED STATES PATENT OFFICE.

EDWARD E. REDFIELD, OF GLENDALE, OREGON.

FIREARM.

1,111,234.

Specification of Letters Patent. Patented Sept. 22, 1914.

Application filed August 1, 1913. Serial No. 782,464.

To all whom it may concern:

Be it known that I, EDWARD E. REDFIELD, a citizen of the United States, residing in Glendale, Douglas county, State of Oregon, have invented certain new and useful Improvements in Firearms, of which the following is a specification, reference being had to the accompanying drawings, which form a part hereof.

10 This invention relates particularly to magazine or repeating firearms of the "slide-action" type in which the several operations of extracting and ejecting the empty shell, placing the fresh cartridge in the chamber 15 of the barrel and cocking the hammer are performed by the reciprocating movement of the fore-end or grip-piece which is generally mounted on the magazine tube below the barrel. Usually, in firearms of this description, the barrel is fixed with respect to the frame or receiver while the fore-end and slide bar are movable with respect to the barrel as well as with respect to the frame or receiver, but in the present case the barrel is 20 movable longitudinally with respect to the frame or receiver and the fore-end and slide bar have only a limited movement with respect to the barrel, the barrel and the fore-end moving together throughout the movement of the barrel. The immediate result of 25 this construction is simplification and compactness, but it results also, as compared with other firearms of like character, such as those shown and described, for example, in Letters Patent of the United States No. 30 1,031,373, dated July 2, 1912, and in application for Letters Patent of the United States No. 744,627, filed January 28, 1913, in a considerable change in the devices which are 35 concerned directly with the extraction and ejection of the empty shell, the placing of a 40 fresh cartridge in the chamber of the barrel, and the cocking and releasing of the hammer. All of the novel features of construction, some of which are capable of use in 45 other structures and general combinations than those shown and described herein, will be more fully explained hereinafter with reference to the accompanying drawings in 50 which they are illustrated and in which—

Figure 1 is a view in elevation of a rifle pistol in which the present improvements are embodied. Fig. 2 is a partial view of the same, partly in elevation and partly in 55 longitudinal section and on a larger scale, the parts being shown in the positions which they occupy when the gun is closed and

ready to be fired. Fig. 3 is a view similar to that shown in Fig. 2 but with the parts in the positions which they occupy when the gun has been fired and the slide bar has been moved a short distance forward in the act of opening the gun. Fig. 4 is a view similar to that shown in Fig. 2, but with the parts in the positions which they occupy when the gun has been fully opened, the empty shell extracted and ejected and a fresh cartridge placed in position for introduction into the chamber of the barrel when the gun is closed. Fig. 5 is a view in horizontal section on the plane indicated by the broken line 5—5 of Fig. 2. Fig. 6 is a detail view in horizontal section on the plane indicated by the broken line 6—6 of Fig. 4. Fig. 7 is a view in perspective which shows particularly the relation of the slide bar to the rear end of the barrel frame. Fig. 8 is a detail view of the hammer with its cocking pawl. Fig. 9 is a detail view in section on the plane indicated by the broken line 9—9 of Fig. 8. Fig. 10 is a perspective view of the sear. Fig. 11 is a perspective view of the lifter. Fig. 12 is a perspective view of the ejector. Fig. 13 is a perspective view of the slide bar locking lever.

In the firearm shown in the drawings the barrel *a*, chambered to receive the cartridge, is secured in or is formed integral with a barrel frame or breach *a'* which is grooved longitudinally as at *a²* to engage longitudinal ribs *c'* of the receiver *c*, has rearward projections *a³* to enter recesses in the frame *d*, when the gun is closed, for the purpose of resisting the breaking tendency when the gun is fired, has on its rear face a tapered vertical projection *a⁴* to enter a corresponding recess in the forward face of the frame for the purpose of centering the barrel accurately when the gun is closed, has on its under side a projection *a⁵* for coöperation with the slide bar as hereinafter described, and has in its lower portion, below the chamber of the barrel, a chamber *a⁶* which forms the rearward continuation of the chamber of the magazine *b*, the rear upper wall of the chamber being beveled or inclined upwardly and rearwardly, as clearly shown in Fig. 4. The magazine *b* is provided as usual with a spring-pressed follower *b'*, by which the cartridges are pressed rearwardly in the magazine. The frame *d*, which supports the longitudinally movable barrel *a* and the other working parts, is suitably formed to receive such working parts, its forward upper face

forming the breech-block d' . The breech-block is recessed as at d^2 to receive the head of the cartridge, the sides of the recess being grooved vertically as at d^3 , to guide the rim of the cartridge when the cartridge is being lifted into position. It is also slotted, as at d^4 , for the firing pin. It receives in its right hand side an extractor shown at d^5 in Figs. 5 and 6, the extractor being of usual construction. Below that portion of the receiver which forms the breech-block, the receiver is open to permit the movement of the slide bar rearwardly and the movement of the lifter, as hereinafter explained.

The usual fork-end h is mounted on the magazine b and has a limited longitudinal movement with respect thereto. Secured to the fore-end is the slide bar h' which has in its upper face a recess k^2 for coöperation with the projection a^5 on the under side of the breech a' , the recess k^2 being slightly longer than the projection so that the slide bar may have a limited movement with respect to the breech, while the continued movement of the slide bar, in either direction, carries the breech and barrel with it. The purpose of the limited relative movement is to lock and unlock the breech and barrel to and from the frame. The locking latch k^3 is pivotally mounted in the under side of the breech a' and passes forwardly and downwardly through an opening, indicated at k^4 , in the slide bar h' , the upper and lower walls of the opening as well as the upper and lower sides of the latch k^3 being suitably beveled so that, at the beginning of the opening movement, when the fore-end and slide bar move relatively to the breech and barrel, the latch k^3 is lifted from behind the shoulder d^5 of the frame, by which the barrel was held in closed position, the barrel being thereby released for the opening movement. Similarly, at the end of the closing movement of the gun the relative movement of the slide bar h' causes the latch k^3 to be thrown down behind the shoulder d^5 , whereby the barrel is locked in its closed position.

In rear of the aperture k^4 , the slide bar h' has on its under side a notch k^5 for engagement with the shoulder m' of the slide-locking lever or latch m , as shown in Fig. 2, such latch being pivoted in the frame as at m^2 and having, forward of the trigger guard, a finger piece m^3 and also having, rearwardly of the shoulder m' , a cam finger m^4 for a purpose to be explained.

In rear of the notch k^5 , the slide bar h' has in its under side a notch k^6 which, when the gun is closed, stands above a toe o' of the trigger o , so that the trigger can then be moved to release the hammer. When the gun is not closed and the notch k^6 is not in line with the toe o' of the trigger the trigger cannot be moved to release the hammer.

In rear of the notch k^6 the slide bar has on its right hand side a pivot lug k^7 for engagement with the cocking link hereinafter referred to. The slide bar is centrally slotted, as at k^8 , to permit the movement of the lifter and it has on its upper side two lugs k^9 , which are beveled off at their forward ends. These lugs move between the lugs a^3 of the breech and act as a cut-off to prevent the rearward movement of the next cartridge from the magazine when the cartridge has already been placed, in the opening movement of the gun, in position for introduction into the chamber of the barrel. The rear cross bar k^{10} of the slide bar contacts with the lifter, as hereinafter described, and preferably is chamfered or rounded off for this purpose.

The lifter l , shown in detail in Fig. 11, and in its operative relation in Figs. 2, 3 and 4, is pivoted at l' in the frame and has a projecting pin l^2 which overlies the slide bar, when the latter is in rear of its forward position, and prevents the forward end of the lifter from falling too far. The lifter has a forwardly projecting finger l^3 which underlies the head of the cartridge which projects rearwardly from the magazine when the opening movement of the gun commences. It has also on its under side, forward of its pivot, a cam projection l^4 with which the cross bar k^{10} of the slide bar co-operates in the latter part of the forward movement of the slide bar to raise the lifter, and with it the cartridge, to its highest position. It has also a rearwardly and downwardly extending finger l^5 with which the cross bar k^{10} of the slide bar co-operates during the last part of its rearward movement, in order to throw the lifter down to its extreme low position, the pin l^2 then entering a shallow, beveled notch k^{11} in the upper side of the slide bar, just to the rear of the lugs k^9 . This beveled notch coacts with the pin to begin the upward movement of the lifter, to start the cartridge into the guide grooves, at the beginning of the forward movement of the slide bar. It has also on its upper side a shoulder l^6 which co-operates with a corresponding shoulder on the hammer to start the hammer rearwardly, during the last part of the forward movement of the slide bar, so that the hammer pawl, hereinafter referred to, may engage properly the hammer lever also hereinafter referred to, and also so that the firing pin shall be withdrawn out of the path of the head of the fresh cartridge as it is moved upward by the lifter.

The hammer h shown most clearly in Figs. 3, 4, 8 and 9, is longitudinally movable in the frame or receiver d and is driven forward by a hammer spring h' when released by the sear i which is shown by itself in Fig. 10. The hammer has on its under side a shoulder

h^2 for engagement with the shoulder l^6 of the lifter l as hereinbefore described and for engagement with the shoulder i' of the sear i . It has also formed therewith the firing pin h^3 which is projected, when the hammer is released, through a suitable opening provided therefor in the breech-block, as clearly shown in Fig. 3. The hammer has pivotally mounted therein a hammer pawl h^4 which is held normally by a spring h^5 in the position indicated in Fig. 8, but can be swung from that position in either direction, the pawl having in its forward end a notch h^6 .

The sear i is pivotally mounted in the frame on the same pin with the lifter l and, having the shoulder i' in rear of the pivot for engagement with the hammer, is extended downwardly in front of the pivot somewhat in L-shape, having at the lower extremity of the forward arm i^2 a lug i^3 which underlies the slide bar and overlies the trigger o at the left of the lug o' thereon.

The cocking-lever p , shown in Figs. 2, 4, 5 and 6, and in part in Fig. 3, is pivoted in the frame as at p' and has on its left hand side a shoulder p^2 , shown in dotted lines in Fig. 4, which is adapted to engage the notch h^6 of the hammer pawl h^4 . At its lower end, as at p^3 , the cocking-lever p engages a link p^4 which is pivoted on the slide bar, the link forming a connection between the slide bar and the cocking-lever. Normally, when the hammer is in its forward position, the notch h^6 of the pawl h^4 is forward of the shoulder p^2 of the cocking-lever, but the initial rearward movement of the hammer, through the action of the lifter l as hereinbefore described, moves the hammer back slightly so that the notch h^6 then engages the shoulder p^2 , so that when the cocking-lever is swung backward by the rearward movement of the slide bar the hammer, through the pawl h^4 , is moved rearwardly until its shoulder h^2 is engaged by the shoulder i' of the sear i . It will be observed that during the rearward movement of the hammer with the cocking-lever the pawl h^4 , having its notch h^6 engaged by the shoulder p^2 , swings upward from its normal position, and that when the hammer is released by the slipping of the shoulder p^2 rearwardly and upwardly from the notch h^6 the pawl, being then disengaged from the shoulder p^2 , swings down under the shoulder p^2 , its notched end h^6 passing slightly forward of the shoulder p^2 . It will also be observed that in the forward movement of the hammer it slides upon the inclined rear end m^4 of the slide lock m and throws the rear end of the lock downwardly so that as soon as the firing pin strikes the cartridge the slide bar is unlocked and the gun made ready to be opened by the forward movement of the fore-end and barrel.

65 The ejector, shown at t in Figs. 5, 6 and

12, is mounted in a suitable cavity in the frame and is thrown forward by a spring t' , excessive forward movement being prevented by a pin t^2 . The ejector is slotted longitudinally, as at t^3 , to form, adjacent to the axis of the gun, a spring finger t^4 which is provided, on the side adjacent to the axis of the gun, with a lug t^5 which is beveled on its rear side, so as to slip over the rim of the cartridge in the rearward movement of the ejector when it is pushed back by the barrel in the closing movement. In the rear-most position of the ejector the lug t^5 stands behind the rim of the cartridge, so that when the ejector is released, in the forward movement of the barrel the lug t^5 engages the rim of the cartridge and snaps the empty shell out to the right. The spring member t^4 acts as a spring holder for the cartridge when the cartridge is pressed upward into place by the lifter.

In describing the operation of the firearm as a whole, so far as that may be necessary, it may be assumed first that the gun is closed with the hammer cocked, and in readiness to be discharged, the parts being then in the positions shown in Fig. 2. A pull upon the trigger o presses the forward end i^2 of the sear i upward and the rear end downward, thereby releasing the hammer and permitting it to be thrown forward by the spring h' so that the firing pin h^3 may strike the head of the cartridge and explode it. The movement of the trigger necessary to release the hammer is possible only when the gun is closed and all of the parts are in proper position for firing by reason of the fact that only at that time is the notch h^6 in the under side of the slide bar k' in a position with respect to the lug or toe o' of the trigger to permit its effective movement. In the forward movement of the hammer h the forward end of the hammer pawl h^4 yielding downwardly passes under the shoulder p^2 of the cocking-lever p . In the last part of the forward movement of the hammer it rides upon the inclined rear end m^4 of the slide lock m and throws it down, withdrawing the shoulder m' from the notch k^5 in the under side of the slide bar k' , thereby unlocking the slide bar and placing it in readiness to be drawn forward by movement of the fore-end k . Although the slide bar is thus released at or even slightly before the instant of explosion, the period is so brief that it is practically impossible to move the fore-end forward until the cartridge has been exploded. When the cartridge in the chamber of the barrel has been exploded the empty shell is held to the breech-block by the co-action of the extractor d^5 and the spring member t^4 of the ejector t . At this time the next cartridge from the magazine rests upon the forward end of the lifter l , substantially as shown in Fig. 130.

3, with the rim of its head in or just below the grooves d^3 at the sides of the breech-block, resting also upon the lugs k^9 on the upper side of the slide bar. If the gun is now to be opened the fore-end k is grasped by the hand and pushed forward. As already described the fore-end has a limited movement with respect to the barrel, the effect of which is to raise the latch k^3 from behind the shoulder d^5 , whereby the barrel also is released from the frame so that it may be drawn forward in the continued movement of the fore-end. This forward movement of the barrel extracts the empty shell from the chamber of the barrel, or draws the barrel from the empty shell which is held against the breech-block as already described and, when the barrel has been drawn part way forward, so that the empty shell is disengaged from the chamber of the barrel, the ejector t snaps forward and ejects the empty shell.

In the beginning of the movement of the slide bar the cross bar k^{10} thereof moves from under the tail l^5 of the lifter and leaves the lifter free, but as the slide bar approaches the forward limit of its movement the bar k^{10} acts against the cam projection l^4 to raise the forward end of the lifter from the position indicated in Figs. 2 and 3 to the position indicated in Fig. 4, the fresh cartridge being thereby carried upward from the position shown in Fig. 3 to the position shown in Fig. 4, the cartridge being guided by the engagement of its rim with the grooves d^2 , above mentioned. At the same time the lugs k^9 on the upper side of the slide bar, which, at the beginning of the movement of the fore-end were drawn forward with respect to the barrel so as to prevent the movement rearwardly of the next cartridge, are holding that next cartridge in the chamber below the barrel, as shown in Fig. 4. In the movement of the bar k^{10} of the slide bar from below the tail l^5 of the lifter as already described the lifter at first rises slightly at its forward end, and as the slide bar approaches the forward limit of its movement the forward end of the lifter is raised, as already described, not only lifting the fresh cartridge completely into position but at the same time, through the action of the shoulder l^6 on the lifter against the shoulder h^2 of the hammer, drawing the hammer back slightly so as to withdraw the firing pin h^2 from the path of the head of the cartridge and also drawing the notched end of the latch h^4 on the hammer back of the shoulder p^2 of the cocking-lever, so that such notched end of the pawl may move into the path of the shoulder p^2 in its rearward movement. In the rearward movement of the fore-end and barrel, the slide bar and barrel at first travel together and during this part of the movement the shoulder p^3

of the cocking-lever p , engaging the notched end of the pawl h^4 and swinging backward, moves the hammer itself against the pressure of the spring h' until the hammer is engaged by the sear. The movement of the cross bar k^{10} of the slide bar from beneath the cam projection l^4 of the lifter permits the forward end of the lifter to fall and if the lifter should stick the cross bar, acting against the under side of the lifter in rear of its pivot, will throw the forward end of the lifter down and finally the cross bar, acting against the tail l^5 of the lifter will throw the forward end of the lifter down to its lowest position. Finally the relative movement of the fore-end with respect to the barrel takes place and thereby the latch k^3 is caused to drop behind the shoulder d^5 of the frame and to lock the barrel in its firing position. The gun is now in readiness to be fired and the cycle of operations to be repeated.

It will be understood that various changes in details of construction and arrangement may be made without departing from the spirit of the invention and also that some of the features of construction herein shown and described may be used to advantage in other combinations than that shown and described herein.

I claim as my invention:—

1. In a firearm, the combination of a receiver, a barrel longitudinally movable in the receiver, a slide bar also movable longitudinally in the receiver, devices to connect the barrel and slide bar, and a slide lock cooperating directly with the slide bar.
2. In a firearm, the combination of a receiver having a locking shoulder, a barrel movable longitudinally in the receiver, a slide bar also movable longitudinally in the receiver and having a limited movement with respect to the barrel, a slide lock cooperating with the slide bar, and a latch carried by the barrel and actuated by the relative movement of the slide to lock and unlock the barrel.
3. In a firearm, the combination of a receiver having a locking shoulder, a barrel movable longitudinally in the receiver, a slide bar also movable longitudinally in the receiver and having a limited movement with respect to the barrel, a slide lock cooperating with the slide bar, and a latch pivotally mounted on the barrel and adapted to engage the shoulder of the receiver, the slide bar having shoulders to engage the latch and actuate it in the relative movement of the slide bar.

4. In a firearm, an ejector which comprises a longitudinally movable rod slotted longitudinally to form a spring member to press laterally against the cartridge.

5. In a firearm, an ejector which comprises a longitudinally movable rod, said

rod being slotted longitudinally to form a yielding member and said member provided on its lateral face with a lug to engage the cartridge rim.

5 6. In a firearm, an ejector which comprises a longitudinally movable rod, said rod being slotted longitudinally to form a yielding member and said member provided on its lateral face with a lug to engage the 10 cartridge rim, said lug having a beveled rear face and a flat front face.

7. In a firearm, the combination of a receiver, a barrel movable longitudinally in the receiver and an ejector mounted mov- 15 ably in the receiver, said ejector having a longitudinal yielding member with a lug on its lateral face to engage the head of the cartridge.

8. In a firearm, the combination of a receiver, a slide bar having in its under side a notch, a hammer, an L-shaped pivoted sear having at its forward and lower end a projecting lug and a trigger to coöperate with the projecting lug of the sear and having a 25 toe to enter the notch of the slide bar when the gun is closed.

9. In a firearm, the combination of a receiver, a barrel movable longitudinally in the receiver, a magazine movable with the 30 barrel, and a slide bar also movable longitudinally in the receiver and having a limited movement with respect to the magazine, said slide bar having a lug to prevent the exit of a cartridge from the magazine when 35 the slide bar is in its forward position relative to the magazine.

10. In a firearm, the combination of a receiver, a longitudinally movable hammer mounted in the receiver and a pivoted lifter 40 also mounted in the receiver, the hammer and the lifter having coöoperating shoulders whereby the hammer is withdrawn slightly from its extreme forward position by the operative movement of the lifter.

45 11. In a firearm, the combination of a receiver, a hammer movable longitudinally in the receiver and having a firing pin and a pivoted lifter mounted in the receiver, the hammer and the lifter having coöoperating 50 shoulders whereby the hammer is withdrawn slightly from its extreme forward position by the operative movement of the lifter.

12. In a firearm, the combination of a receiver, a hammer and a lifter, the hammer and lifter being both mounted in the frame the lifter on a fixed axis and having operative connections whereby the hammer is moved by the movement of the lifter.

60 13. In a firearm, the combination of a receiver, a lifter pivotally mounted therein

and having a lateral pin forward of its pivot and a slide bar to co-act with said pin during the rearward movement of the slide bar to support the lifter and having in its upper 65 side a shallow beveled notch to coöperate with said pin at the beginning of the movement of the slide bar and start the upward movement of the lifter.

14. In a firearm, the combination of a receiver, a lifter pivotally mounted therein and having forward of its pivot a laterally projecting pin and having on its under side forward of the pin a cam projection and a slide bar having in its upper side a tapered 75 notch to coöperate with said pin to start the movement of the lifter during the beginning of the forward movement of the cross bar and having at its rear end a cross bar to coöperate with said cam projection to complete the movement of the lifter during the 80 last of the forward movement of the slide bar.

15. In a firearm, the combination of a receiver, a lifter pivotally mounted therein 85 and having a tail piece extended to the rear of the pivot and inclined downwardly, and a slide bar having at its rear end a cross bar to coöperate with the tail piece and effect the downward movement of the forward 90 end of the lifter.

16. In a firearm, the combination of a receiver, a lifter pivotally mounted therein and having on its under side, forward of the pivot, a cam projection and having a tail 95 piece inclined downwardly at its rear end, and a slide bar having at its rear end a cross bar to coöperate with the cam projection and raise the lifter at the end of the forward movement of the slide bar and to coöperate 100 with a curved tail piece during the last of the rearward movement of the slide bar to lower the lifter.

17. In a firearm, the combination of a receiver, a hammer, a hammer pawl mounted 105 on the hammer, a cocking-lever and a slide bar, the cocking-lever having operative engagement with the pawl and operative connections with the slide bar.

18. In a firearm, the combination of a receiver, a hammer, a spring-pressed hammer pawl yieldable in either direction from normal position, a cocking-lever pivotally mounted in the receiver and adapted to engage the pawl and a slide bar connected to 110 the cocking-lever.

This specification signed and witnessed this 26th day of July A. D., 1913.
